DRAFT-GEAR.

1,343,296.

Specification of Letters Patent. Patented June 15, 1920.

Application filed September 25, 1915. Serial No. 52,672.

To all whom it may concern:

Be it known that I, HARRY F. WOERNLEY, a citizen of the United States, and resident of Pittsburgh, county of Allegheny, and State of Pennsylvania, have invented certain new and useful Improvements in Draft-Gears, of which the following is a specification, and which are illustrated in the accompanying drawings, forming a part thereof.

The invention relates to draft gears of the type in which the cushioning effect is principally obtained by the frictional engagement of alternated plates having relative longitudinal movement. Draft gears of this type are shown in the patent to Cotton and Henderson, No. 989,949, of April 18, 1911, and in my copending application for patent on draft gear, Serial No. 49,225, filed September 7, 1915. The object of the present invention is to provide a draft gear of the said type which shall be of improved construction and increased efficiency, the improvement residing more particularly in the provision of means for insuring full frictional contact between the engaging surfaces, coupled with freedom of release after compression.

The invention is exemplified in the construction which is hereinafter described and is illustrated in the accompanying drawings, wherein,

Figure 1 is a detail plan view of the underframing of a railway car showing the draft gear principally in central section, but with some parts in plan,

Fig. 2 is a side view of the draft gear partly in section and also showing details of the coupler and yoke,

Fig. 3 is similar to Fig. 1, but shows more of the draft gear in plan view and with the parts in the positions which they would occupy if completely compressed in draft,

Fig. 4 is a detail plan view of the draft gear, and

Figs. 5, 6 and 7 are perspective views showing details of the construction.

Details of the two center sills of a railway car are indicated at 10, 10, the draft and buffing lugs being shown at 11, 11 and 12, 12, respectively. The coupler butt is shown at 13, and the yoke or tail strap at 14. The draft gear preferably includes a casing 15, the front end wall of which is directly engaged with the coupler butt 13 and with the draft lugs 11, 11, while a rear

follower plate 17, engageable with the upright rear end portion 18 of the yoke 14 and with the buffing lugs 12, 12, is provided, as usual.

As shown, the rear end 19 of the casing 15, is open. Within the casing 15 are contained two springs 20, 21, a pair of spring followers 22, 23, and two groups 24, 25, of alternated friction plates 26, 27. The springs 20, 21, are conveniently located upon the axis of the gear, the spring 21 being weaker than the spring 20 and being inclosed within it. These springs react between the end wall 16 of the case 15 and the spring followers 22, 23, respectively, the follower 23 moving through a central opening 28 in the follower 22.

The friction plates 26 of each group 24, 25, are preferably anchored against longitudinal movement with reference to the casing 15. For this purpose, each of the plates 26 may be provided at both its top and bottom with a lug 29 which projects into a transverse recess 30 (Fig. 4) in the corresponding wall of the case whereby lateral movement of the plates is permitted. The friction plates 27 are longer than the plates 21, and are free to move both longitudinally and laterally. These plates normally project through the open end 19 of the case for engagement with the follower 17. If desired, the plates 26 may be of wedge shape, their forward ends being the thicker, as in my said pending application for patent on draft gear, Serial No. 49,225.

A set of four coöoperating wedge blocks 31, 32, 33, 34, are located between the two groups 24, 25, of friction plates. The wedge blocks 31 and 32 are longitudinally disposed and engage the followers 17 and 22, respectively. The wedge block 31 is engaged with the spring follower 23 through the medium of a stem 35 which projects through an opening 36 in the wedge block 32. The wedge block 32 accordingly extends in front of the follower 23 and is recessed, as at 37 (Fig. 5) to clear the same.

The wedge blocks 33 and 34 are transversely disposed, and are located upon opposite sides of the central plane of the wedge blocks 31 and 32. Each of the wedge blocks 33, 34, is slidingly engaged with both of the wedge blocks 31 and 32 and with the adjacent friction plate 27 of the corresponding group 24 or 25. A key 38 serves

to hold the parts in assembled relation when the draft gear mechanism is not applied to the car, as also to retain the springs 20, and 21, under slight tension. This key is shown as being extended vertically through the case 15 and through an opening 39 in the stem 35 of the wedge block 31. In order that the key 38 may not interfere with the compression of the gear, both the top and bottom walls of the case 15 are recessed in line with the key, as at 40 (Fig. 4).

In the compression of the gear by draft, the follower 17 moves forwardly, advancing the wedge block 31 against the effort of the spring 21 and thereafter sliding the friction plates 27 forwardly between the plates 26. The forward movement of the wedge block 31, tends to advance the wedge blocks 33 and 34, but this movement is resisted by the spring 20 acting through the follower 22 and wedge block 32. Outward pressure is accordingly exerted by the wedge blocks 33, 34 for increasing the frictional resistance to the movement of the plates 27 between the plate 26. If the plates 26 are of wedge shape, as shown, the outward pressure exerted by the wedge blocks 33, 34, is augmented, as the parts approach the position of ultimate compression illustrated in Fig. 3, by reason of the narrowing of the space between the two groups 24, 25, of friction plates toward their forward ends. Furthermore, the wedge shape of the plates 26 results in an inclination of the plates 27 with reference to the direction of movement of the follower 17. The pressure exerted by the follower 17 against the plates 27 thereby adds to the force with which each of these plates bears against the next adjacent plate 26. When the gear is compressed by buffing stresses, the action is the same but is brought about by a movement of the casing 15 toward the follower 17, the latter remaining stationary.

When the pressure upon the gear is released, the spring 21 serves to separate the follower 17 and case 15 but a sudden reduction of the outward pressure upon the two groups 24, 25, of friction plates is prevented by the accompanying expansion of the spring 20. The wedge blocks 33, 34, are confined only by their engagement with the friction blocks 31, 32, and with the inner friction plates 27 of the two groups 24, 25. Each of these wedge blocks is accordingly free to assume the proper position for making a flat contact with the adjacent friction plate, even though the friction plates 27 are inclined to the line of draft by reason of the wedge shape of the friction plates 26. A full frictional contact between all of the sliding parts is thereby assured.

When the plates 27 are inclined to the line of draft, as shown, the wedge blocks

33, 34, are so positioned that their outer faces are correspondingly inclined. The set of wedge blocks 31, 32, 33, 34, considered together, thereby constitute a wedge with one of its inclined faces presented to the friction plates of each group 24, 25. With this arrangement the relative forward movement of the wedge blocks 33, 34, between the two groups of friction plates 24, 25, causes the wedge blocks 33, 34, to approach each other. This, in turn, effects a separation of the wedge blocks 31, 32, thereby increasing the forward movement of the follower 22 and the compression of the spring 20. However, the wedge shape of the friction plates 26, the use of wedging means presenting a wedge face to a group of alternating plates, and the combination of a group of alternated plates and wedging means therefor with the contacting faces of the wedging means and the adjacent plate inclined to the direction of relative movement are not claimed broadly in this application for the reason that such claims are presented in my said application, for patent on draft gear, Serial No. 49,225, filed September 7, 1915.

I claim as my invention,—

1. In a draft gear, in combination, a pair of independent spring followers facing in the same direction and an opposed follower, a pair of longitudinally disposed oppositely facing wedges, one being engaged by the said opposed follower and extending to one of the said spring followers and the other being engaged by the remaining spring follower only, a pair of opposed transverse wedges each coöperating with both of the first mentioned wedges, and a group of alternated relatively fixed and longitudinally movable friction plates engaged for lateral compression by each of the said transverse wedges, the plates of one set in each group being engageable with the said opposed follower.

2. In a draft gear, in combination, a pair of independent spring followers facing in the same direction and an opposed follower, a pair of longitudinally disposed oppositely facing wedges, one being engaged by the said opposed follower and extending to one of the said spring followers and the other being engaged by the remaining spring follower only, a pair of opposed transverse wedges each coöperating with both of the first mentioned wedges, and a group of alternated relatively fixed and longitudinally movable friction plates engaged for lateral compression by each of the said transverse wedges, the plates of one set in each group being wedge shaped and the plates of the other set in each group being engageable with the said opposed follower.

3. In a draft gear, in combination, a group of alternated relatively fixed and lon-

- gitudinally movable friction plates the plates of one set being wedge shaped, a pair of relatively movable oppositely facing longitudinal wedges located at one side of the
- 5 group of friction plates, a laterally facing wedge slidingly engaging both of the longitudinal wedges and acting upon the adjacent friction plate and an abutment against which the pair of wedges laterally react.
- 10 4. In a draft gear, in combination, a group of alternated relatively fixed and longitudinally movable friction plates the plates of one set being wedge shaped, a pair of relatively movable oppositely facing longitudinal wedges located at one side of the group of friction plates, a laterally facing wedge having sliding engagement with both of the longitudinal wedges and with the adjacent friction plate and an abutment against which the pair of wedges laterally react.
- 15 5. In a draft gear, in combination, two groups of alternated relatively fixed and longitudinally movable friction plates the plates of one set in each group being wedge shaped, a pair of relatively movable oppositely facing longitudinal wedges and a pair of relatively movable oppositely facing transverse wedges located between the two groups of friction plates, each of the said
- 20 transverse wedges being in sliding engagement with both of the said longitudinal wedges.
- 25 6. In a draft gear, in combination, two groups of alternated relatively fixed and longitudinally movable friction plates the plates of one set in each group being wedge shaped, a pair of relatively movable oppositely facing longitudinal wedges and a pair of relatively movable oppositely facing transverse wedges located between the two groups of friction plates, each of the said
- 30 transverse wedges being in sliding engagement with both of the said longitudinal wedges.
- 35 7. In a draft gear, in combination, two groups of alternated relatively fixed and longitudinally movable friction plates, a pair of independent spring followers facing the two groups of friction plates at one end, an opposed follower facing the two groups of friction plates at the other end, a pair of longitudinally disposed oppositely facing wedges and a pair of oppositely facing
- 40 transverse wedges located between the two groups of friction plates, one of said longitudinally disposed wedges being engaged by the said opposed follower and extending to one of the said spring followers, the other longitudinally disposed wedge being engaged by the remaining spring follower only and each of the said transverse wedges
- 45 and each of the said transverse wedges being in sliding engagement with both of the said longitudinally disposed wedges and with the inner friction plate of the adjacent group, the friction plates of one set in each of the said groups being wedge shaped and the friction plates of the other set in each of said groups being engageable with the said opposed follower.
- 50 8. In a draft gear, in combination, two groups of alternated relatively fixed and longitudinally movable friction plates, a pair of independent spring followers facing the two groups of friction plates at one end, an opposed follower facing the two groups of friction plates at the other end, a pair of longitudinally disposed oppositely facing wedges and a pair of oppositely facing
- 55 transverse wedges located between the two groups of friction plates, one of said longitudinally disposed wedges being engaged by the said opposed follower and extending to one of the said spring followers, the other longitudinally disposed wedge being engaged by the remaining spring follower only and each of the said transverse wedges being in sliding engagement with both of the said longitudinally disposed wedges and with the inner friction plate of the adjacent group,
- 60 9. In a draft gear, in combination, a group of alternated friction plates, adjacent plates having relative longitudinal movement, a pair of oppositely facing longitudinally disposed wedges located at one side of the group of plates, a transverse wedge having sliding engagement with both of the longitudinally disposed wedges and with the adjacent friction plate, the contacting faces of the transverse wedge and friction plate being oblique to the direction of relative movement between said parts and an abutment against which the pair of wedges laterally react.
- 65 10. In a draft gear, in combination, two groups of alternated friction plates, the plates of the two groups being inclined to each other and adjacent plates of each group having relative longitudinal movement, and two pairs of oppositely facing relatively movable wedge blocks located between the two groups of plates, the wedge blocks of one pair being longitudinally disposed and the wedge blocks of the other pair being transversely disposed, each of the transversely disposed wedge blocks being in sliding engagement with both of the longitudinally disposed wedge blocks and presenting a flat face for sliding contact with one of the groups of friction plates which is inclined to correspond with the inclination of the group of friction plates with which it is engaged.
- 70 11. In a draft gear, in combination, a group of alternated friction plates, adjacent plates having relative longitudinal movement, a pair of oppositely facing longitudi-

the friction plates of one set in each of the said groups being engageable with the said opposed follower.

75 8. In a draft gear, in combination, two groups of alternated relatively fixed and longitudinally movable friction plates, a pair of independent spring followers facing the two groups of friction plates at one end, an opposed follower facing the two groups of friction plates at the other end, a pair of longitudinally disposed oppositely facing wedges and a pair of oppositely facing transverse wedges located between the two groups of friction plates, one of said longitudinally disposed wedges being engaged by the said opposed follower and extending to one of the said spring followers, the other longitudinally disposed wedge being engaged by the remaining spring follower only and each of the said transverse wedges being in sliding engagement with both of the said longitudinally disposed wedges and with the inner friction plate of the adjacent group, the friction plates of one set in each of the said groups being wedge shaped and the friction plates of the other set in each of said groups being engageable with the said opposed follower.

80 9. In a draft gear, in combination, a group of alternated friction plates, adjacent plates having relative longitudinal movement, a pair of oppositely facing longitudinally disposed wedges located at one side of the group of plates, a transverse wedge having sliding engagement with both of the longitudinally disposed wedges and with the adjacent friction plate, the contacting faces of the transverse wedge and friction plate being oblique to the direction of relative movement between said parts and an abutment against which the pair of wedges laterally react.

85 10. In a draft gear, in combination, two groups of alternated friction plates, the plates of the two groups being inclined to each other and adjacent plates of each group having relative longitudinal movement, and two pairs of oppositely facing relatively movable wedge blocks located between the two groups of plates, the wedge blocks of one pair being longitudinally disposed and the wedge blocks of the other pair being transversely disposed, each of the transversely disposed wedge blocks being in sliding engagement with both of the longitudinally disposed wedge blocks and presenting a flat face for sliding contact with one of the groups of friction plates which is inclined to correspond with the inclination of the group of friction plates with which it is engaged.

90 11. In a draft gear, in combination, a group of alternated friction plates, adjacent plates having relative longitudinal movement, a pair of oppositely facing longitudi-

100 10. In a draft gear, in combination, two groups of alternated friction plates, the plates of the two groups being inclined to each other and adjacent plates of each group having relative longitudinal movement, and two pairs of oppositely facing relatively movable wedge blocks located between the two groups of plates, the wedge blocks of one pair being longitudinally disposed and the wedge blocks of the other pair being transversely disposed, each of the transversely disposed wedge blocks being in sliding engagement with both of the longitudinally disposed wedge blocks and presenting a flat face for sliding contact with one of the groups of friction plates which is inclined to correspond with the inclination of the group of friction plates with which it is engaged.

105 11. In a draft gear, in combination, a group of alternated friction plates, adjacent plates having relative longitudinal movement, a pair of oppositely facing longitudi-

nally disposed wedges located at one side of the group of plates, a spring opposing the movement of one of the said wedges, a transverse wedge having sliding engagement with both of the longitudinally disposed wedges and with the adjacent friction plate, the contacting faces of the transverse wedge and friction plate being oblique to the direction of relative movement between said parts and an abutment against which the pair of wedges laterally react.

12. In a draft gear, in combination, two groups of alternated friction plates, the plates of the two groups being inclined to each other and adjacent plates of each group having relative longitudinal movement, two coöperating pairs of oppositely facing relatively movable wedge blocks located between the two groups of plates, the wedge blocks of one pair being longitudinally disposed and the wedge blocks of the other pair being transversely disposed, and a spring opposing the outward movement of the longitudinally disposed wedge block at that end at which the two groups of friction plates are nearest to each other.

pair being transversely disposed and a spring opposing the movement of one of the said longitudinally disposed wedge blocks.

25

13. In a draft gear, in combination, two groups of alternated friction plates, the plates of the two groups being inclined to each other and adjacent plates of each group having relative longitudinal movement, two coöperating pairs of oppositely facing relatively movable wedge blocks located between the two groups of plates, the wedge blocks of one pair being longitudinally disposed and the wedge blocks of the other pair being transversely disposed, and a spring opposing the outward movement of the longitudinally disposed wedge block at that end at which the two groups of friction plates are nearest to each other.
